UNITED STATES PATENT OFFICE.

FRANK W. MEYER, OF OSHKOSH, WISCONSIN, ASSIGNOR TO THE OSHKOSH TRUNK COMPANY, OF OSHKOSH, WISCONSIN, A CORPORATION OF WISCONSIN.

TRUNK LOCK.

Application filed September 28, 1922. Serial No. 591,027.

To all whom it may concern:

Be it known that I, FRANK W. MEYER, a citizen of the United States, residing at Oshkosh, in the county of Winnebago and 5 State of Wisconsin, have invented new and useful Improvements in Trunk Locks, of which the following is a specification.

This invention relates to locking devices for wardrobe and other trunks, and broadly 10 is of the general type covered by my Reissue Patent No. 14,143, granted May 30, 1916, wherein the manipulation of the locking hasp on the outside of the trunk operates a plurality of locks at spaced points inside of 15 the trunk, thus locking the latter at a number of points in its length.

One object of my present invention is to provide a locking mechanism wherein all the locks are arranged outside of the trunk, thus 20 avoiding the use of the inside locks as heretofore and giving more room in the trunk, and furthermore doing away with weakening any of the trunk parts by avoiding cutting holes in them to accommodate the inside 25 locks, as heretofore, and moreover allow for any vertical spacing of the drawers in the drawer section without being hampered or interfered with by any of the locking members of the trunk.

30 Another object of my present invention is to provide a mechanism which will automatically draw the two trunk sections together when the locking members are brought into engagement for locking the 35 trunk and automatically push them apart when the locking mechanism is moved into position to unlock the trunk, thereby mechanically and positively overcoming any friction that may be exerted against the 40 trunk sections when standing on the floor to resist bringing the trunk sections together throughout all portions of their length when closing them or hindering opening when the trunk is unlocked.

45 A further object of my invention is to provide a locking mechanism which is simple in its construction and operation and which may be readily applied to the outside of the trunk, thus saving expense and labor in 50 installing the same.

The invention consists further in the matters hereinafter described and more particularly set forth in the appended claims.

In the accompanying drawings—

55 Fig. 1 is a front view of a wardrobe trunk

equipped with a locking mechanism of my invention, the trunk sections being shown closed and locked;

Fig. 2 is a like view showing the trunk 60 still closed but unlocked;

Fig. 3 is a perspective view of said trunk showing the two hinged sections thereof unlocked and swung into open position;

Fig. 4 is an enlarged view of the locking fixture removed from the trunk to more 65 clearly show the manner in which the end-wise movable rod is connected with the swinging hasp and the several movable locking members;

Fig. 5 is a view partly in section of one 70 of the locking devices operated by said rod, the parts being shown in locked positions;

Fig. 6 is a like view of the same parts when unlocked; and

Fig. 7 is a horizontal sectional view taken 75 on line 7—7 of Fig. 6.

The wardrobe trunk shown in Figs. 1 to 3 is of the center opening type, that is, it has two hinged together upright sections 1 and 2, with a hinged lid 3 closing the open upper end of the wardrobe section 1. The other section 2 has a closed upper end and is provided with a plurality of drawers 4, 4. The latter are slidably supported in an open frame secured in the section 2 against the top, bottom, and side walls thereof, as in trunks of this general kind. This frame has side members 5, 5 secured to the side walls of the section 2 to reinforce them and top and bottom members 6, 7 against the top and bottom walls of said trunk section, as shown in Fig. 3. From the latter, it will be noted that the side members 5, 5 are continuous and unbroken from top to bottom.

The side walls of the wardrobe section 1 are reinforced by cleats 8, 8. These extend from the bottom of said section up to near the upper end thereof and are continuous and unbroken throughout, as shown in Fig. 3, except where they have shallow notches to receive the lugs on the shoe box 9 at the bottom of said section. The upper end of this section 1 carries the extensible trolleys 10, 10 for the garment hangers 11, 11 and also the side racks for the clothes retainer or compressor 12, as in trunks of the kind illustrated herein.

The locking fixture of my invention comprises, broadly, a plurality of locking devices 13, 14, 14, all located on the outside of 110

the trunk, together with an operating rod 15 inside of the trunk and carried by the wardrobe section 1.

The locking device 13 comprises a locking hasp made in two hinged together sections 16 and 17, the latter being fixed to a stub 18 rotatably mounted in the section 1. Said stub 18 is connected by a link 19 with the rod 15 in somewhat the same manner as disclosed in my said Reissue Patent No. 14,143. The hasp section 17 carries at its swinging end a key-operable locking mechanism to enter and lock in a receiving socket 20 on the outside of the drawer section 2 as in said reissue patent.

Each locking device 14 comprises members 21, 22 secured by rivets 23, 23 to the respective trunk sections 1 and 2 in alignment and adjacent the meeting edges of said sections. The drawer section 2 is provided with a valance or metal strip 24 on the outside and surrounding the open edge thereof. This valance projects beyond such edge and overlaps the opposed edges of the wardrobe section 1 when the trunk is closed. The forward part of the member 22 is secured to this valance and the rear part to the trunk section 2. Said member 22 is recessed on its inside, as at 25, to accommodate the valance strip 24, as shown in Fig. 7. Said member 22 is provided with a forwardly projecting fixed locking member 26 provided with a slot or eye 27 to be engaged by a movable locking member 28 in the other member 21.

The member 21 is in the form of a hollow casing to house the locking member 28, there being a chamber 29 in said casing for that purpose, as shown in Figs. 5 to 7. Said casing 21 is set back from the adjacent edge of the trunk section 1 to permit the valance strip 24 to overlap the same when the trunk is closed. The locking member 28 is fixed to a relatively short pin or stud 30 rotatably carried by the trunk section 1 and extending therethrough and through the outer wall of the casing 21. The portion of the stud 30 on which the locking member 28 is mounted is preferably made square to fit in a square opening in the locking member so that by rotating the stud 30 the locking member will be turned. The inner end of the stud 30 projects into the inside of the trunk section 1 behind the adjacent cleat 8, as shown in Fig. 7, and is there connected with the bar 15 by a link 31. The outer end of the stud 30 is provided with an enlarged head countersunk in the outer wall of the casing 21 to provide a bearing for such end of the stud and also to make a flush finish. The fixed locking member 26 enters the casing 21 through a slot or opening 32 in the inner edge thereof, as shown.

As illustrated in Figs. 5 and 6, the movable locking member 28 is provided on one

side with a somewhat hook-shaped locking projection 33 to enter the slot or eye 27 in the fixed locking member 26 when the latter extends into the casing 21. Said locking member 28 is also provided with a cam shaped projection 34 to operate against the end of the fixed locking member 26 for moving the trunk sections apart while the locking devices are being unlocked.

When the trunk sections 1, 2 are closed and locked, the parts occupy the positions shown in Fig. 1 and the hooks 33 of the locking members 28 are engaged with the fixed locking members 26, as shown in Fig. 5.

To unlock the trunk, the hasp 18 is unlocked from its socket 20, swung outward from the same, and then rotated or turned bodily upward into the upright position shown in Fig. 2. During this movement, the bar 15 is moved endwise upward through the link 19 and by the links 31, 31 the several movable locking members 28 are turned downward carrying their locking projections or hooks 33 out of the eyes 27 in the fixed locking members 26. The parts in such positions are detailed in Fig. 6. As the members 28 are thus turned, their cam projections 34 operate against the ends of the fixed locking members 26 to force them away from the casing 21, thereby mechanically and positively pushing or moving the two trunk sections 1 and 2 apart, as shown in Fig. 2. This separates the trunk sections 1, 2 sufficiently to readily and easily open them. This separating action is automatic during the actuation of the locking fixture and overcomes any friction of the trunk on the floor to resist the opening movement.

To lock the trunk, the sections 1 and 2 are brought together into the position shown in Fig. 2. Complete closing of the trunk is prevented, at this time, by the members 26 contacting against the cam projections of the locks 28, as shown in Fig. 6. Turning the hasp 13 downward moves the bar 15 downward and turns the locks 28, carrying their hooks 33 into the eyes or slots 26. As the hooks 33 are turned into the eyes 27 they operate on the members 26 to draw the trunk sections 1 and 2 into tight contact, as shown in Fig. 1. When this has been accomplished, the locking hasp 13 is swung into locked engagement with its socket 20 and the trunk is locked throughout. This drawing action is also automatic and, being mechanical, overcomes any friction of the trunk on the floor to hinder or retard the closing of the sections.

By the construction shown and described, the trunk is locked at a plurality of points in its length and all of the locking devices are on the outside of the trunk. This does away with all locks inside. Having all of the locks on the outside avoids cutting holes

or slots through the reinforcing walls or cleats 5 and 8 of the two trunk sections and thus prevents weakening them. This also allows the drawers 4 in the section 2 to be 5 made all the same horizontal length because no space is needed at the ends of several of the drawers to accommodate the inside locks, as heretofore. Moreover, this allows the drawers 4 to be spaced apart vertically any 10 distance required, and permits making the drawers of whatever depth desired.

The locking devices 14 having the function of automatically and positively drawing the two trunk sections together when the locks 15 are locked and automatically and positively moving them apart when the locks are unlocked, is of great advantage. It overcomes any resistance that may be offered by the weight of the trunk on the floor or the 20 floor covering to hinder proper closing of the trunk sections because the mechanism is positive and pulls the trunk sections together at several parts in their height regardless of what resistance may be offered. 25 It also overcomes any resistance to hold the trunk sections together when they are unlocked, and thus makes opening and closing of the trunk easy and permits it being done with convenience and dispatch because it is 30 not necessary to reach down and close the gap which would necessarily be should there be no means provided adjacent the bottom of the trunk for this purpose. Locating all 35 of the locking devices on the outside of the trunk saves expense and labor in applying the same.

While I have shown and described herein in detail a trunk locking mechanism of my invention, it is of course to be understood 40 that the details of construction and arrangement of parts may be variously changed and modified without departing from the spirit and scope of my invention.

I claim as my invention:

45 1. The combination with a trunk having two hinged together sections, of locking means therefor, comprising a plurality of spaced locking devices carried by said sections and all located on the outside thereof, one of said locking devices consisting of a movable locking hasp on one section and a co-operating part therefor on the other section, the other of said locking devices having co-operating locking members on the 50 respective trunk sections, and means carried by one of said sections and actuated by said hasp on being turned into and out of a position substantially parallel to the adjacent edges of said trunk sections for locking and unlocking said last named locking members.

60 2. The combination with a trunk having two hinged together sections, of locking means therefor, comprising a plurality of spaced locking devices carried by said sec-

tions and all on the outside thereof, one of said locking devices consisting of a movable locking hasp on one section and a co-operating part therefor on the other section, the other of said locking devices having fixed 70 and movable locking members on the respective trunk sections, and an endwise movable bar carried by one of said sections on the inside thereof and actuated by said hasp for moving said movable locking members into 75 and out of locking engagement with the fixed ones.

3. The combination with a trunk having two hinged together sections, of locking means therefor, comprising a plurality of 80 spaced locking devices carried by said sections, one of said locking devices consisting of a movable locking hasp on one section and a co-operating part therefor on the other section, the other of said locking devices having co-operating locking members on the respective trunk sections, and means carried by one of said sections and actuated by said hasp for locking and unlocking said locking members, the latter having co-acting 85 means for automatically and positively drawing the trunk sections together on being locked and moving the sections apart on being unlocked.

4. The combination with a trunk having 90 two hinged together sections, of locking means therefor, comprising a plurality of spaced locking devices carried by said sections and all located on the outside thereof, one of said locking devices consisting of a 100 movable locking hasp on one section and a co-operating part therefor on the other section, the other of said locking devices having fixed and movable locking members on the respective trunk sections, and an endwise movable bar carried by one of said sections on the inside thereof and connected with said movable locking members for moving the same, said bar being actuated by said hasp for moving said movable locking members into and out of locking engagement with the fixed ones, said locking members having coacting means for automatically and positively drawing said sections together on being locked and moving the sections apart on being unlocked.

5. The combination with a trunk having 110 two hinged together sections, of locking means therefor, comprising a plurality of locking devices carried by said sections along the front edges thereof and arranged between and adjacent the top and bottom of the trunk, said locking devices being all 120 located on the outside of said sections, the upper locking device consisting of a locking hasp rotatably mounted on one section and a receiving socket therefor on the other section, the other locking devices having fixed locking members on one section and movable locking members rotatably mount- 125 130

ed on the other section, an endwise movable bar carried by one of said sections on the inside thereof and connected by links with said movable locking members, and means 5 connecting said bar with said hasp for turning the movable locking members into and out of locking engagement with the fixed ones on turning said hasp.

6. The combination with a center opening 10 wardrobe trunk having two hinged together sections, of locking means therefor, comprising a plurality of locking devices carried by said sections along the front edges thereof and arranged between and adjacent 15 the top and bottom of the trunk, the upper locking device being on the outside of the sections and consisting of a movable locking hasp on one section and a co-operating part therefor on the other section, the other 20 locking devices having fixed and movable locking members on the respective sections, and means carried by one of said sections and actuated by said hasp for locking and unlocking said locking members, the latter 25 having coacting means for automatically and positively drawing the trunk sections tightly together along the entire length thereof on being locked and separating the trunk sections by moving them apart on being 30 unlocked.

7. The combination with a trunk having two hinged together sections, of a locking means therefor, comprising a plurality of spaced locking devices carried by said sections, one of said locking devices being 35 located on the outside of said sections and consisting of a movable locking hasp on one section and a co-operating part therefor on the other section, the other of said locking 40 devices each having a fixed locking member with a slot therein on one section and a movable locking member rotatably mounted on the other section, said movable locking members having locking hooks to be moved 45 into and out of locked engagement with the slots in said fixed members, and means carried by one of said sections and actuated by said hasp for turning said movable locking members.

50 8. The combination with a trunk having two hinged together sections, of locking means therefor, comprising a plurality of spaced locking devices carried by said sec-

tions, one of said locking devices being located on the outside of said sections and 55 consisting of a movable locking hasp on one section and a co-operating part therefor on the other section, the other of said locking devices each having a fixed locking member with a slot therein on one section and a movable locking member rotatably mounted 60 on the other section, said movable locking members having locking hooks and cam projections, the latter operating on the adjacent ends of the fixed locking members to 65 move the trunk sections apart on being unlocked and the former to enter said slots and to lock and draw the sections together on being locked, and means carried by one of said sections and actuated by said hasp 70 for turning said movable locking member into and out of locking engagement with the fixed ones.

9. The combination with a trunk having two hinged together sections, of locking 75 means therefor, comprising a plurality of spaced locking devices carried by said sections, one of said locking devices being located on the outside of said sections and consisting of a movable locking hasp on 80 one section and a co-operating part therefor on the other section, the other of said locking devices each having a fixed locking member with a slot therein on one section and a movable locking member rotatably mounted 85 on the other section, said movable members having hooks and cam projections, the latter operating against the adjacent ends of the fixed locking members to move the sections apart on being unlocked and the former entering said slots to draw and lock the sections together on being locked, means carried by one of said sections and actuated by said hasp for turning the movable locking members into and out of locking engagement with the fixed ones; and a casing housing each of the movable locking members having an opening therein to allow the associated fixed locking member to enter and be withdrawn from the same in closing and opening of said sections. 90 100

In testimony that I claim the foregoing as my invention, I affix my signature, this 22nd day of September, A. D. 1922.

FRANK W. MEYER.
